PROCESS FOR RECOVERING CHEMICALS FROM AQUEOUS SOAP SOLUTIONS

Dwight B. Mapes and Truman P. Moote, Jr., Tulsa, Okla.,
assignors to Pan American Petroleum Corporation, a
corporation of Delaware

Application March 8, 1956, Serial No. 570,237

6 Claims. (Cl. 260—450)

The present invention relates to a method for the recovery of various oxygenated organic chemicals from solutions thereof. More particularly, it pertains to a process for recovering in substantially pure form a relatively high percentage of oil soluble alcohols from crude hydrocarbon or other mixtures containing carbonyl compounds.

While the principles taught herein find application in the recovery of chemicals from numerous kinds of crude mixtures, the present description deals particularly with the problems encountered in recovering valuable chemicals from the oil stream produced by the hydrogenation of carbon monoxide in the presence of a fluidized alkali-promoted iron catalyst under known synthesis conditions. This oil fraction obtained in the hydrocarbon synthesis process, contains a rather wide variety of acids, carbonyl compounds (ketones and aldehydes), and alcohols together with a small proportion of esters. For example, in hydrocarbon synthesis plants designed to produce approximately 640,000 lbs. per day of liquid hydrocarbons, there are simultaneously produced along with this oil fraction 108,000 lbs. of oil soluble carbonyl compounds, 93,000 lbs. of oil soluble alcohols, 32,000 lbs. of esters, and 83,000 lbs. of oil soluble acids. Owing to their value as chemicals, it is desirable to separate these compounds from the oil stream as completely as possible. Also in the subsequent conversion of the aforesaid oil fraction into gasoline, it is imperative that such compounds either be removed from the oil or converted into substances such as, for example, unsaturated hydrocarbons, which can then be utilized in conjunction with the hydrocarbons originally synthesized to make high quality motor fuels.

Because of the proximity in boiling points of these various oil soluble chemicals to the hydrocarbons constituting the oil fraction, separation of chemicals from hydrocarbons by normal fractional distillation methods is a practical impossibility.

In recovering oil soluble chemicals from hydrocarbon solutions thereof, it has been proposed that soap solutions of various types be employed as selective solvents or extractants for such chemicals. Generally, these "soap" solutions are not composed of soaps in the true sense, but are made up largely of substantially non-surface-active salts of alkali metals or their equivalent salts derived from carboxylic acids having an average molecular weight ranging from about 85 to about 135. Soap solutions of this type are most conveniently prepared by adding the required amount of caustic or other suitable base to the primary oil fraction produced in hydrocarbon synthesis whereby the free acids present in said fraction are neutralized. By agitation of the resulting mixture, a substantial portion of the oil-soluble chemicals present therein tend to pass into the lower aqueous layer. Along with the chemicals dissolved in the soap solution, there is usually found from about 5 to 10 weight percent of hydrocarbons solubilized therein. The latter, generally speaking, are undesirable because they tend to impart objectionable characteristics to the chemicals recovered from such solutions. Separation of the hydrocarbons from the

2

chemicals has been a relatively difficult job since the former boil over substantially the same range as the chemicals, making ordinary distillation separation methods of little value.

5 In practice, primary oil from hydrocarbon synthesis was first mixed with sufficient caustic to neutralize the free acids in the oil, the resulting soaps forming a lower aqueous phase which separated from the neutral oil. The neutral oil was next extracted with a lean soap solution of the type hereinafter defined and the resulting extract, which contained oxygenated chemicals and solubilized hydrocarbons, was combined with the chemical-rich soap solution formed in the above-mentioned neutralization step. These combined streams were then subjected to extraction with a light hydrocarbon (hereinafter referred to as "deoiling" or "the deoiling step") such as for example, liquid propane or liquid butane, for the purpose of removing from the soap solution any hydrocarbon dissolved by the soap in the neutralization and extraction steps. 10 The raffinate from this extraction consisted chiefly of an oil-free soap solution containing oil-soluble oxygenated organic chemicals and was thereafter fractionated under pressure to separate any light hydrocarbon solvent present after which the soap solution was stripped free of chemicals in a conventional fractionating still. The light hydrocarbon extract obtained from the deoiling step contained both high molecular weight hydrocarbons and relatively high molecular weight chemicals, particularly ketones and esters, and was generally sent to a flash drum or to a distillation unit where the butane was removed overhead and returned to the deoiling step. The bottoms from the butane recovery step consisted principally of hydrocarbons and chemicals and was recycled and combined with the neutral oil feed to the soap extraction step. 15 20 25 30 35 40 45 50

Under such conditions, however, a rather substantial buildup of chemicals, chiefly high molecular weight ketones and esters, occurred in the soap extractor requiring higher soap to oil ratios to remove these chemicals. Owing to the use of such higher oil to soap ratios, the quantity of dissolved hydrocarbons in the resulting extract increased, thereby requiring increased amounts of butane in the deoiling operation. In other words, it was found that larger and larger quantities of light hydrocarbon extractant were required to produce a rich soap extract which contained a minimum concentration of hydrocarbons. To avoid this difficulty, the bottoms from the butane recovery step containing an appreciable quantity of chemicals was withdrawn from the system and either discarded therefrom or separately processed to recover the chemicals and hydrocarbons as individual fractions.

Accordingly, it is an object of our invention to provide a process whereby the chemicals in a hydrocarbon solution thereof can be substantially completely recovered free of hydrocarbon contaminants. It is another object 55 of our invention to effect a further separation of carbonyls and/or esters from alcohols present in said hydrocarbon solutions to give a fraction of such alcohols substantially free from both hydrocarbons, carbonyls and/or esters. Another object of our invention is to recover a substantially pure alcohol fraction from an aqueous solution comprising alcohols, carbonyls and dissolved hydrocarbons in contaminating amounts, by contacting said solution with a liquid light saturated hydrocarbon under controlled conditions of temperature, pressure and volume ratios of said light hydrocarbon to said aqueous solution to selectively extract said contaminating hydrocarbons and carbonyls in separate extraction steps from said aqueous solution to yield a solution of alcohols substantially free of hydrocarbons and carbonyls.

60 65 70 75 80 85 90 95 Briefly we accomplish the above and other objects of our invention by controlling both the temperature of the light hydrocarbon employed to deoil the original soap

extract and the volume ratio of light hydrocarbon to aqueous soap extract employed.

In carrying out the process of our invention the conditions employed in the first extraction step should be closely controlled in order to obtain the desired results. Thus to achieve the required selectivity, extraction of contaminating hydrocarbons by means of a liquid light hydrocarbon should be effected at a volume ratio of liquid light hydrocarbon to soap extract ranging from about 1:10 to about 1:4. With these volume ratios temperatures from above 80° F. up to slightly below, i. e. about 5° below, the critical temperature of the light hydrocarbon may be employed. In the case of propane the preferred extraction temperature ranges from about 140° to about 180° F. while temperatures ranging from about 160° to about 200° F. are considered most desirable for the butanes. At temperatures in the range of 80° F. and below, the selective solvent power of propane decreases substantially causing increasing amounts of chemicals to be extracted from the soap along with dissolved hydrocarbons. This particular extraction step is preferably carried out under conditions such that a single stage of contacting between the solvent and the soap extract occurs. With more than two extraction stages the quantity of chemicals extracted with the contaminating hydrocarbons becomes substantial. Accordingly, this first extraction step should be conducted in a short extraction zone in which only one or two stages of contact are favored.

In this connection the terms "single stage" or "single extraction stage," as used in the present description and claims, is intended to refer to a condition produced or prevailing within an extraction column wherein a given volume of solvent is used to extract a fixed volume of feed to yield raffinate and extract phases corresponding to those resulting from a batch extraction where solvent and feed are permitted to reach equilibrium. When the expressions "multi-stage extraction" or "multi-stage extractor" are used such terms are intended to refer to a plurality of extraction stages in a column in which the solvent countercurrently contacts the feed to be extracted. In a case of this type a five stage extraction would be defined as a system having five different equilibrium stages or the equivalent thereof, in which the solvent and the feed are countercurrently contacted. Multi-stage extraction in carrying out the second extraction step of our invention is desirable, with equipment providing for from five to ten extraction stages generally being preferred.

An additional factor to be considered in the first extraction step, i. e. the step in which only dissolved hydrocarbons are removed from the soap extract, is that lower volume ratios of light hydrocarbon solvent to soap are required to remove dissolved hydrocarbons from selected soap solutions, the latter constituting alkali metal or equivalent salts of C₂ to C₆ aliphatic carboxylic acids. Lower volume ratios of light hydrocarbon solvent to soap are required in the above instance because extracts obtained by the use of such soap solutions generally contain less contaminating hydrocarbons and such hydrocarbons are more readily removed. On the other hand with soap solutions of the higher molecular weight soaps, i. e. those prepared from carboxylic acids having an average molecular weight of from about 125 to about 135, higher volume ratios of solvent to soap extract are ordinarily needed because such soaps extract larger amounts of hydrocarbons from the HCS oil and such hydrocarbons are more difficult to selectively remove from soap extracts of this type.

Pressures which may be employed in the first-mentioned extraction step range from a minimum of about 140 p. s. i. for propane at a temperature of about 80° to 85° F. to a practical maximum of about 500 p. s. i., with pressures in the range of 300 to 400 p. s. i. being preferred at temperatures in the range of 140° to 180° F. Higher pressures, of course, may be used, however, the advantage to be gained at pressures in excess of 500 p. s. i. tend to

be overcome rather rapidly by increased compression costs. Minimum pressures for the butanes when used in this same step are in the neighborhood of 25 to 50 p. s. i. at temperatures of 80° to 85° F. However, when using the butanes as the light hydrocarbon extractant temperatures of the order of 160° to 200° F. are ordinarily preferred, using pressures in the range of from about 125 to about 235 p. s. i.

In the second extraction step the minimum pressures for propane range from about 115 to about 140 p. s. i. at temperatures of from 65° to 85° F. Corresponding pressures for the butanes over the same temperature range vary from about 20 to about 50 p. s. i.

The expression "carbonyls," as used herein, is intended to cover esters as well as ketones and aldehydes.

After dissolved hydrocarbons have been removed from the soap by means of the first extraction step the hydrocarbon-depleted soap extract is next countercurrently extracted with liquid light hydrocarbon in volume ratios of light hydrocarbon to soap ranging from about .5:1 to about 2:1 at temperatures of from about 65° to about 85° F. For both propane and the butanes the preferred temperature is in the neighborhood of from 70° to 80° F. while the pressures employed over this range may vary from about 120 to about 135 p. s. i.

Soap solutions employed to obtain the extracts used as feed in the process of our invention may range in concentration of from about 20 to 50 weight percent. With concentrations above 50 weight percent some difficulty is encountered owing to the fact that at such concentrations the soap tends to form a gel. With soap solutions of 50 weight percent or less gels are produced when using pentane or high molecular weight solvents due to the solubility of the soap in the higher hydrocarbons. Accordingly, we desire to restrict the light hydrocarbon solvents used in our process to propane and the butanes, propane generally being preferred.

The process of our invention may be described in further detail by reference to the accompanying flow diagram wherein, for example a chemically rich soap extract resulting from the extraction of a neutral HCS oil with a lean aqueous soap solution is fed into the upper portion of a single stage extraction column 2 through line 4. Countercurrently, liquid propane at a pressure of 325 p. s. i. is introduced through line 6, at a lower level, into column 2. The temperature within the extraction zone is about 150° F., the pressure being in the neighborhood of about 325 p. s. i. Overhead through line 8 an extract of hydrocarbons from the aforesaid rich soap phase dissolved in propane is withdrawn. The quantity of hydrocarbons in the propane extract represents all of said hydrocarbons present in the original extract fed to the column. Only a relatively small percentage of the chemicals is taken overhead with the stream in line 8. Said stream after being reduced in pressure to about 200 p. s. i. by means of valve 10 is next sent to column 12, operated at a bottoms temperature of about 150° F., where a mixture of hydrocarbons is removed through line 14. Overhead propane vapors, at 200 lbs. pressure, are taken off through line 16, cooled in condenser 18 to a temperature of about 75° F. and then sent to liquid propane storage tank 20 which is maintained at about 200 p. s. i. The hydrocarbons in line 14 are sent to column 22 operated at a bottoms temperature of 150° F. The pressure on this mixture is reduced to atmospheric by means of valve 24 prior to entering column 22. In this column propane is taken off overhead through line 26 and sent to high pressure (200 p. s. i.) propane line 16 after being brought up to that pressure by means of compressor 28. A liquid propane reflux is maintained in column 22 by injection through line 30. Under the conditions of operation hydrocarbons boiling above propane are removed as bottoms through line 32.

The raffinate withdrawn from column 2, through line 34, consists essentially of a hydrocarbon-free aqueous

soap extract containing carbonyls and alcohols. This stream, after being cooled to about 75° to 80° F. in cooler 36 and reduced in pressure to about 200 p. s. i. by means of valve 38, is next transferred to a multi-stage extraction column 40 where it is introduced at an upper portion thereof and is countercurrently contacted by a liquid stream of propane, introduced through line 42 and transferred therethrough from storage tank 20 by means of pump 44. The temperature within the extraction zone of column 40 is maintained at 75° to 80° F. Although the pressure required to hold the propane in the liquid phase within the aforesaid temperature range varies from about 125 to about 150 p. s. i., we prefer to employ a pressure of about 200 p. s. i. at this stage in order to maintain flow of overhead from column 40 through subsequent portions of the system. The quantity of propane introduced into the system is such as to give a volume ratio of propane to aqueous soap solution introduced through line 34 of about 1:1. Overhead the resulting propane extract is withdrawn through line 46 and contains substantially all of the carbonyls and/or esters and a portion of the alcohol present in the original charge to column 2 leaving an aqueous soap solution containing alcohols, but substantially free from carbonyls, to be withdrawn through line 48. The stream in line 48 is next sent to stripping column 50 where it is introduced into an upper portion thereof. Within this column separation of the aqueous and organic (alcohol) phases is effected with the concentrated soap phase being withdrawn as bottoms through line 52, where it may be further purified if desired or used without further purification in a subsequent extraction of neutral HCS oil to provide additional feed for column 2. The overhead from column 50 is withdrawn through line 52 and condenser 54 and allowed to stratify in separator 56. The water layer is returned to the stripping column as reflux through line 58 while the upper organic layer, consisting essentially of product alcohols, is withdrawn through line 60.

The overhead from column 40 passes through flow control valve 62 and thereafter is introduced into column 64 operated at a bottoms temperature of about 150° F. and at a pressure of about 200 p. s. i., i. e., the pressure corresponding to the vapor pressure prevailing in storage tank 20 which may range from about 140 to about 200 p. s. i. Gaseous propane at 200 p. s. i. is taken off through line 66 and combined with propane in line 16. The bottoms, consisting chiefly of carbonyls and some alcohols together with a small amount of propane is then transferred through line 68 and pressure relief valve 70 to column 72. Column 72 is operated at atmospheric pressure and at a temperature of about 150° F. A liquid propane reflux is supplied to the column through line 74 supplied by line 6. Carbonyls together with some alcohols are withdrawn from the bottom of column 72 through line 76. Under the conditions of operation all of the propane in column 72 passes out the top thereof through line 78 where it joins propane also at atmospheric pressure in line 80. These combined streams then pass through line 80 and into line 26. This gas is next passed through compressor 28 and delivered into line 16 at a pressure of about 200 p. s. i.

The ability of the process of our invention to separate hydrocarbons and carbonyls from soap extracts of the above mentioned type, leaving a soap solution of substantially pure alcohols, is further illustrated by the following specific example.

Example

About 800 cc. of an extract comprising a 50 weight percent aqueous soap solution and oil soluble alcohols (0.430 g. mol) and carbonyls (0.222 g. mol) together with contaminating hydrocarbons obtained by extraction of a nonacidic HCS oil fraction is subjected to a single stage extraction step with about 200 cc. of liquid propane at a temperature of about 150° F. and at a pressure of

about 340 p. s. i. The soap employed in securing the initial extract (feed) is derived from aliphatic acids having an average molecular weight ranging from about 125 to about 135. In this extraction step approximately 98 to 100 weight percent of the contaminating hydrocarbons dissolved in the soap extract are removed. The raffinate from the last extraction is next subjected to further treatment in a tower having five extraction stages. At a point near the base of this tower liquid propane is added at a rate such that the volume ratio of propane to soap extract is about 1:1. Within the extraction zone the temperature is maintained at about 75° F. and the pressure employed is about 130 p. s. i. Under these conditions a rising stream of propane removes from a descending charge of soap extract about 97 mol percent of the carbonyls and about 45 mol percent of the alcohols. Total chemicals extracted from the initial feed amounts to about 75 mol percent. The extracted stream of chemicals, however, on separation can be subjected to mild hydrogenation in accordance with known conditions to produce a mixture of secondary and primary alcohols free from hydrocarbons. After the second extraction step the soap solution contains approximately 55 mol percent of the alcohols present in the original soap extract. Such soap solution is free from hydrocarbons and contains no more than about 3 mol percent of the carbonyls originally present.

One of the outstanding features of the process of our invention is the fact that we are able to secure a highly purified fraction of primary product alcohols. This fact is important because in the use of such alcohols such as, for example in the manufacture of plasticizers it is desired that the plasticizers be free from both hydrocarbons and reaction products of secondary alcohols. Experience has shown that materials containing plasticizers having such impurities therein, tend to discolor on exposure or aging. Plasticizers made from primary alcohols of the type recovered in the process of our invention, however, have been found to retain good color and plasticizing properties over extended periods.

From the foregoing description and example, it is apparent that the process of our invention affords a convenient method for recovering oil soluble alcohols in highly purified form from complex mixtures containing close boiling hydrocarbons and carbonyl compounds. Our invention, therefore, in its broadest aspect, contemplates accomplishing the above results by controlling, within relatively narrow limits, the temperature, pressure and the volume ratio of solvent to feed.

We claim:

1. In a process for the recovery of a substantially pure alcohol fraction from a 20 to 50 weight percent aqueous carboxylic acid soap solution comprising carbonyls and alcohols of the type found in the hydrocarbon phase produced by the Fischer Tropsch synthesis and contaminating amounts of dissolved hydrocarbons, said soap being derived from a mixture of fatty acids having an average molecular weight ranging from about 85 to about 135, wherein said soap solution is contacted with a liquid light saturated hydrocarbon having from 3 to 4 carbon atoms, the improvement which comprises first extracting said soap solution with said light hydrocarbon in a volume ratio of light hydrocarbon to said solution of from about 1:10 to 1:4 at a temperature ranging from about 80° F. to not more than about 5° F. below the critical temperature of said light hydrocarbon and at minimum pressures ranging from about 25 to 50 p. s. i. for the C₄ hydrocarbons to about 140 p. s. i. for the C₃ hydrocarbon, said extraction being carried out in an extraction zone of not more than about one stage, thereafter subjecting the raffinate from said extraction, which raffinate is now substantially free from contaminating hydrocarbons, to a second extraction step in a multi-stage extraction zone having not more than about ten stages, wherein said raffinate is extracted with a liquid

light hydrocarbon having from 3 to 4 carbon atoms, the volume ratio of said light hydrocarbon to said raffinate ranging from about 5:1 to about 2:1, at a temperature of from about 65° to about 85° F. and at a minimum pressure of from about 115 to about 140 p. s. i. for the C₃ hydrocarbon and from about 20 to about 50 p. s. i. for the C₄ hydrocarbon to yield a raffinate containing alcohols substantially free of said contaminating hydrocarbons and carbonyl compounds.

2. The process of claim 1 in which liquid propane is employed as the liquid light hydrocarbon, the temperature employed in the first extraction step is from about 140° to about 180° F. and the temperature at which said second extraction step is carried out is from about 70° to about 80° F.

3. The process of claim 1 in which n-butane is employed as the liquid light hydrocarbon, the temperature employed in the first extraction step is from about 160° to about 200° F. and the temperature at which said second extraction step is carried out is from about 70 to 80° F. with pressures in the first extraction step being at a minimum of 125 p. s. i., at 160° F., and at a minimum of 235 p. s. i., at 200° F., and pressures in the second step being at a minimum of about 25 p. s. i.

4. The process of claim 1 in which a C₄ hydrocarbon is employed as the liquid light hydrocarbon and the minimum pressures in both extraction steps range from 25 to about 50 p. s. i.

5. The process of claim 4 in which the liquid light hydrocarbon is n-butane.

6. In a process for the recovery of a substantially pure alcohol fraction from a 20 to 50 weight percent aqueous soap solution free from contaminating hydrocarbons but containing alcohols and carbonyl compounds of the type found in the hydrocarbon phase produced by the Fischer Tropsch synthesis, said soap being derived from a mixture of fatty acids having average molecular weight ranging from about 85 to about 135, the improvement which comprises subjecting said soap solution to extraction in a multi-stage extraction zone having not more than about ten stages, wherein said soap solution is extracted with a liquid light hydrocarbon having from 3 to 4 carbon atoms, the volume ratio of said light hydrocarbon to said soap solution ranging from about 5:1 to about 2:1, at a temperature of from about 70° to about 80° F. and at a minimum pressure from about 115 to about 140 p. s. i. for the C₃ hydrocarbon and from about 20 to about 50 p. s. i. for the C₄ hydrocarbon, to yield a raffinate containing alcohols substantially free of said carbonyl compounds.
